D. Evans,

Band Pulley.

Patented Mar. 19, 1834.

(March 19, 1834.) 213.

David Evans of Philadelphia Pennsylvania

Letters Patent

The schedule referred to in these Letters Patent and making part of the same containing a description in the words of the said David Evans himself, of his improvement in "Machines for hoisting of goods, and weights in Stores"

To all to whom these presents shall come
Be it known that I David Evans of the City of Philadelphia in the county of Philadelphia and state of Pennsylvania have invented a new and useful improvement in Hoisting machines, and that the following is a full and exact description of the construction and operation of said machine as invented or improved by me. The machine is in principle neither new nor novel, but is one of the practical first principles of the laws of mechanics, a wheel with hub arms and rim. The power is applied to the wheel around the rim, and into the groove of which passes an endless rope, the weight is drawn up by a rope winding round the horizontal axle, the velocity of the power is to the velocity of the weight as the circumference of the wheel is to the circumference of the axle. I consider the improvement to consist in the form and materials of which this wheel is constructed; principally the material it being iron, either wrought or cast. The wheels heretofore and now being used were and are constructed of wood, the power obtained by this iron wheel acting as a fly wheel is as fifteen to one, a vertical wheel with a horizontal shaft of indefinite size with hub arms and rim to the

214.

groove in the periphery of the wheel in which a soap is inserted the said wheel always to be constructed of Iron Nitreous
